UNITED STATES PATENT OFFICE.

FREDERICK W. WIESEBROCK AND ERNST HUBER, OF NEW YORK, N. Y.;
SAID HUBER ASSIGNOR TO SAID WIESEBROCK.

THERMO-ELECTRIC INDICATOR.

SPECIFICATION forming part of Letters Patent No. 415,758, dated November 26, 1889.

Application filed November 20, 1888. Serial No. 291,338. (No model.)

To all whom it may concern:

Be it known that we, FREDERICK W. WIESEBROCK, a citizen of the United States, residing at New York, in the county and State of New York, and ERNST HUBER, a citizen of Switzerland, residing at New York, in the county of New York and State of New York, have invented new and useful Improvements in Thermo-Electric Indicating Apparatus and 10 Fire-Alarms, of which the following is a specification.

Our invention relates to indicating apparatus of that general type employed in showing changes of temperature, and the purpose 15 thereof is to provide means whereby variations of temperature at any number of different points located in the same electric circuit may be shown at a given central station or point at any instant, and also the increase or fall of temperature above or below 20 a given point or degree, whereby danger of conflagration on the one hand or of any improper or undesired fall of temperature on the other hand may be not only ascertained 25 at any moment, but may also be indicated by a suitable audible alarm located at one or more stations.

It is the purpose of our invention to provide simple mechanism whereby the temperature 30 existing at any one or all of a series of different points or stations may be indicated at any instant at a central or controlling station by the agency of a single index, such apparatus being adapted for use upon loaded 35 vessels to show the temperature of different portions of the hold, and thus avert the danger of spontaneous combustion or fire from other causes, as well as in breweries and distilleries to control the temperature of fermentations, or in drying-chambers and cold 40 storage warehouses, in public halls and hospitals, and stores containing inflammable material.

The invention consists in the several novel 45 features of construction and new combinations of parts hereinafter fully set forth, and then specifically pointed out and defined in the claims following this specification.

Referring to the accompanying drawings, 50 Figure 1 is a plan view of an apparatus containing our invention. Fig. 2 is a section of Fig.

1 in the line x x . Fig. 3 is an elevation of the resistance-drum in Fig. 1, part of the supporting-plates being in section. Fig. 4 is a central vertical section, on an enlarged scale, 55 of one of the thermometers used. Fig. 5 is a cross-section of Fig. 4. Fig. 6 is a diagram showing the several electric circuits. Fig. 7 is an end elevation of the parts by which the indicator-circuits are closed. 60

In the said drawings, the reference-numeral 1 denotes a board or other suitable support, upon which is arranged an electric bridge, preferably of the Wheatstone pattern. This bridge is composed, in part, of a spool 2, of 65 wood or other suitable material, wound between its flanges with fine silk-covered copper wire 3. Within the spool, upon suitable insulated bearing 4, is journaled a shaft 5, upon which is hung a magnetized bar 6, rendered astatic by the construction well known in galvanometers, and so arranged that it is balanced upon the shaft, while its center of gravity is below the latter. Upon the shaft 5 is rigidly mounted an ebonite block 75 7, upon which are mounted two copper springs or strips 8, parallel to each other and to the magnetized bar 6. These copper strips are slightly separated from each other for insulation and are attached to 80 the ebonite block centrally, so that their ends project upon each side thereof, being attached by screws 10, so that there shall be perfect insulation from the shaft. Upon each side of the shaft 5 and beneath the ends 85 of the copper strips 8 is arranged a bracket 12, having an insulated horizontal pin or bar 13, upon which are mounted four copper disks, each disk having a central opening to receive the pin 13. Between said disks are placed 90 insulating-disks 15, of paper, wood, or rubber, and upon the end of the pin 13 is turned a nut 16, to hold the disks in place. Two of the copper disks are arranged beneath the end of one of the copper strips 8, forming a pair 14^a, 95 and the other two beneath the corresponding end of the other strip, forming a pair 14^b. The arrangement upon the other side of the shaft 5, beneath the opposite ends of said copper strips 8, is the exact duplicate of that 100 already described, the copper disks being arranged to form the two pairs 14^c and 14^d, ly-

ing beneath the ends of the copper strips 8. It will be seen that a current of electricity passed through the wire 3 upon the spool in one direction will cause the bar 6 to turn toward a vertical position, thereby rocking the shaft 5 in one direction, while the reversal of the direction of the current will cause a similar movement in the opposite direction. Upon the board 1 is also mounted a motor composed of a permanent horseshoe-magnet 17, supported on a wooden bracket 18, to which it is secured by wooden strips 19. The armature 20 of this magnet is carried by a horizontal shaft 21, having bearing at one end in a block 22, and at the other end in a brass plate 23 having lugs 23^a, by which it is attached to the board 1 at right angles thereto. The armature is composed of a cylindrical bar of soft iron revolving close to the poles of the magnet, the ends of said armature being beveled upon the side immediately in opposition to the poles to secure the maximum effect from the attracting and repelling forces. Upon the armature are slipped spools 24, wound with many layers of fine copper wire, silk-insulated, and forming a continuous circuit, the terminals of the wire being attached to the two parts of the commutator. The latter consists of two semicircular copper plates 25, mounted on a cylindrical insulating-support 26, carried by the shaft. The parts of the commutator are arranged in parallelism with the circle of rotation, and the extremities of said parts are separated from contact by a slight interval, as shown in Fig. 2.

The brushes are composed of copper plates or springs 27 and 28, mounted upon a suitable insulating-support 29 and lying against the revolving parts 25 of the commutator.

In the brass plate 23 are journaled, upon opposite sides of the motor-shaft 21, two independent shafts 30 and 31, both geared by pinions 32 with a small pinion 33 on the end of the dynamo-shaft 21. The other ends of those shafts have bearing in a brass plate 34, parallel with the plate 23. The end of the shaft 30 projects through the plate and through a post 35 lying against it, and upon the projecting end of said shaft is mounted a needle 40 or index 36, lying in front of a dial-plate 37, attached to the post 35.

Upon the shaft 31 is mounted a drum 38, formed of wood or other suitable material. Upon this drum are arranged a series of resistance-coils 39, wound parallel with the axis of rotation and connected in a continuous circuit. Upon the front end of the drum are arranged a circular series of copper plates 40, corresponding, or substantially so, with the intervals between the resistance-coils 39 and separated from each other. One terminal of each coil is connected to one of these plates and the other terminal to the adjacent plate, each plate thus forming the connection for the opposite terminals of adjacent coils. At one point on the drum a single resistance-coil

39 is omitted, forming a break in the continuity of the circuit at the point 41. Upon one side of this point a metal strip or arm 42, mounted on and revolving with the shaft 31, 70 makes contact with the plate 40, lying adjacent to the break. Upon the board 1 is mounted a brass strip 43, rising to a point about in the horizontal line of the axis of the shaft 31, where it makes contact with the 75 plates 40 as the drum revolves. By this arrangement it will be seen that a greater or less number of resistances are inserted in the circuit by the revolution of the drum. For example, in the position shown in Fig. 3 all 80 the coils save one are inserted. Should the drum turn from right to left, a coil will be withdrawn from circuit at each successive contact of a plate 40 with the brass strip 43, until finally, when the strips rest upon the 85 plate making connection with the arm 42, all the resistances will be cut out.

The reference-numeral 44, Figs. 4 and 5, denotes an indicating-thermometer composed of a cast-iron vessel or receptacle 45, containing 90 mercury and having in its upper end or mouth a female thread, which receives a cast-iron cap-nut 46. This nut is provided with a central opening 47, which receives a second cast-iron nut 48, in which is screwed an 95 ebonite tube 49, having a central channel 50. At its top this tube enters a cast-iron cap 51, provided with an overflow-chamber 52. The cap 51 has a nipple 53 projecting upward and passing through but not touching a 100 brass cover 54, forming part of a brass case 55, which surrounds the parts and is screwed upon a collar 56 on the vessel 45.

At regular intervals in the ebonite tube 49 are inserted needles 57, of steel, lying at right 105 angles to the channel 50 and their points entering said channel. The needles are inserted upon opposite sides of the tube alternately, and their outer projecting ends are provided with eyes 58, to which are connected 110 resistances 59, connecting a needle on one side of the tube 49 with the needle alternating therewith and one or more degrees higher in the channel 50 on the other side of said tubes. From the latter needle-eye another 115 similar resistance 59 extends to the third needle, and so on until the upper needle of the series is reached. Thus it will be seen that a continuous spiral of resistances surrounds the tube 49, running from bottom 120 to top, the resistance-coil being equal in number to the resistances upon the drum 38 and being connected to the eyes of the needles 57. Each resistance 59 inserted between two consecutive needles corresponds 125 with the resistance of one of the coils 39 of the drum 38.

The construction of the thermometer is such that it can be adjusted to register either high or low temperature, according to the 130 level to which the volume of mercury is forced by the adjustment of the screw-nuts

46 and 48. If x equals the volume of the chamber 47, then the ratio $\frac{x}{45 x x}$ will be extremely small, and the absolute and relative expansion may be considered equal in both cases. The means for regulating the instrument by the screw-nuts 46 and 48 are very simple and effective, any large alteration of the volume of mercury for correction being accomplished by the adjustment of the screw-nut 46, while the more delicate adjustments and corrections are made by altering the level of mercury by the screw-nut 48, a standard thermometer being used to establish the proper points.

Upon the brass cap 54 of the thermometer and in electrical contact therewith is mounted a binding-screw 60, and upon the other side of the nipple 53 is mounted a second binding-screw 61, insulated from the cap 54 by a washer 62 and having electrical contact with a spring 63, which rests on the nipple 53. The upper coil of the resistances 59 is connected by a wire 63^a with the cast-iron cap 51. It will be seen that as the mercury rises in the channel 50 of the ebonite tube all the resistances 59 below the top of the mercurial column will be cut out of circuit. Any desired number of these thermometers are employed, arranged at different points and in the manner suited to the circumstances of each case.

The electrical circuits will now be described, after which we will point out and explain the means by which the several thermal indications are brought at any moment to the notice of the operator at a central station or point.

The coil of the Wheatstone bridge is supplied by a battery B, from one pole of which runs a wire 64, connected to the brass spring-strip 43. From one of the lugs 23^a on the brass plate 23 extends a conducting-plate 65, on which is a binding-screw 66. From this point a wire 67 connects with one of the terminals of the coil 3 of the Wheatstone bridge by way of a binding-post 68. From the other terminal of said coil the wire 69 is carried to a connection 70, which, for convenience, may be a plate of brass, which is bent to form a flat horizontal plate, a portion of which is mounted on a support 72 near the board 1. Arranged near but not in contact with this plate is a second and similar plate 73, to which is connected a wire 74, leading back to the other pole of battery B. Upon the support 72 are mounted a series of keys 75, each mounted on an elastic brass or other conducting-plate 76, and each having a stem or shank 77 depending below the key and so arranged that as the latter is depressed the said stem will be brought into electrical contact with both of the strips 70 and 73 simultaneously. For this purpose these two brass connecting-strips are brought into parallelism upon the support 72 and are extended thereon for any distance required for the accommodation of

a number of keys corresponding with the number of thermometers and each of said keys numbered or lettered to correspond with a letter or number designating one of the said thermometers. From a binding-screw 78 on each of the elastic plates 76 extends a wire 79, connected to the binding-post 60, or that one of the thermometers which is numbered or otherwise designated to correspond with the number or designation on said key. From the other binding-post 61 on each thermometer a wire 80 is led to a binding-post 81. From this point a wire or plate 82 leads to a binding-post 83, and thence by a wire 84 to binding-post 68.

In the motor-circuit, which is supplied by a battery B', Figs. 1 and 6, a wire 85 leads from the negative pole of the battery to one of the disks forming part of the pair 14^a, and from the other member of this pair a wire 86 leads to the brush 27 of the motor. From the same pole of the battery a wire 87 leads to a disk forming one member of the pair 14^a on the other side of the galvanometer-shaft 5, and from the other member of the same pair of disks 14^a a wire 88 leads to the other brush 28 of the motor. Starting from the other pole of the battery, a wire 89 leads to a disk forming one member of the pair of disks 14^b, while from the other member of the same pair a wire 90 leads to the brush 28 of the motor. From the same pole of the battery, also, a wire 91 leads to one disk of the pair 14^c, while from the other disk of said pair a wire 92 leads to the brush 27 of the motor.

The length of the conductors between the thermometers 44 and the binding-post 66 is compensated by one or more resistance-coils 93, interposed in the circuit 67. It is necessary that the conductors 80 from the binding-post 61 of the thermometers should have the same resistance, or, material and diameter of said conductors being substantially equal, the length should be equal also. In order to satisfy this postulate, we either use conductors 80, having similar lengths, or we interpose resistances 94 at suitable points. This arrangement enables us to connect any number of thermometers with one single indicator.

The automatic forward and backward movement of the motor-armature is one of the main features of the invention.

The battery-circuits being open, let it be supposed that the operator, wishing to ascertain the temperature at the point of location of one of the thermometers, touches that one of the keys 75 having connection with said thermometer through the binding-post 60 on the thermometer-cap. The moment the shank or stem 77 makes contact with the parallel strips 70 and 73 a current flows from one pole of the battery B through wire 64 to the spring 43, where it is divided into two circuits. One circuit is formed by the resistances of the drum 38, the conductor 65, binding-post 66, resistance 93, wire 67, binding-post 68, con-

nection 84, post 83, conductor 82, and the circuit in which the indicators are arranged. The other circuit is formed by the conductor 70, resistances 100, and the keys 75. Between 5 the resistances 100 and the binding-post 68 the Wheatstone bridge is interposed by means of conductor 69. As the drum 38 stands normally with the brass strips upon the zero-point and with all the resistances 10 39 cut out, and as more or less of the resistances 59 in the indicator-circuit will be normally in circuit, the ratio of resistances upon the opposite sides of the Wheatstone bridge will be unequal, and a current will traverse 15 said bridge, causing a deflection of the galvanometer needle or bar 6 and rocking the shaft 5, thereby bringing the ends of the copper strips 8 down upon one side or the other of said shaft 5 and making contact with the 20 two pairs of disks 14^a 14^b or the two pairs 14^c 14^d. The contact of these strips with the two pairs 14^a and 14^b closes the motor-circuit in one direction—as, for example, from the negative pole of the battery by wire 86 to one 25 of the pair of disks 14^a, through one of the copper strips 8, through the other disk 14^a, by wire 86 to the brush 27, and thence by way of brush 28 and wire 90, disks 14^b, the other copper strip 8, and wire 89 back to the other pole 30 of the battery. This gives movement to the shaft of the motor in one direction, thereby revolving the shafts 30 and 31 and moving the index-hand on one shaft and the drum 38 carried by the other shaft. This revolution continues until the resistances inserted 35 by the drum 38 are equal to the resistances 59 in the indicator-circuit, whereupon the current ceases to traverse the Wheatstone bridge, and the motor-circuit is broken. At this moment the index 36 points to a figure on the dial 37, which indicates the temperature at 40 the thermometer. For example, if the mercury in the thermometer rises to the fifth needle, six ohms will be cut out of one branch 45 of the indicator-circuit, and upon closing said circuit the equilibrium of the bridge-circuit is disturbed and the dynamo-circuit closed until as many resistances are inserted by the drum 38 as there are left in the thermometer. 50

The bridge is supplied by one or more Leclanché or other suitable cells, and the motor-circuit is supplied in a similar way. The motor-battery is independent of the bridge-battery. 55

After each indication the index may be allowed to remain at any point to which it was moved by the last operation of the dynamo. If the thermometer rises after the indication, 60 the next test will advance the index correspondingly. If it falls, the test will retract the hand, the motor-current being reversed.

What we claim is—

1. In a heat-indicating apparatus, the combination, with a galvanometer, of an independent motor-circuit closed in opposite directions by copper strips tilted by the deflection 65

of the galvanometer bar or needle, an indicator-circuit forming part of the galvanometer-circuit, a drum containing a series of resistances inserted or cut out of the galvanometer-circuit by rotation of said drum, and a series of thermometers, each having a series of resistances, which are inserted and cut out by the fall and rise of the mercurial column, 70 the circuit of each thermometer and the galvanometer being closed by a key, and the resistance-drum being rotated in either direction by the revolution of the motor, substantially as described. 75

2. In a heat-indicating apparatus, the combination, with a Wheatstone bridge and galvanometer, and a needle or arm mounted thereon, having arms rocked by the deflections of the galvanometer-needle, of a motor, a circuit for said motor closed in opposite directions by the arms of the needle-shaft, an index rotated by the motor, a circuit in which are interposed a series of thermometers each having a series of resistances inserted and 80 cut out by the rise and fall of the mercurial column, a key-circuit, and an independent electric circuit for the Wheatstone bridge, made and broken by the keys of the key-circuit, substantially as described. 85

3. In a heat-indicating apparatus, the combination, with a Wheatstone bridge and with a circuit therefor, of a thermostatic circuit, a signaling-circuit, a series of keys interposed in the latter, a series of thermostats in the 90 thermostatic circuit, and a motor operating an index and having a circuit interposed in a branch of the circuit of the Wheatstone bridge and made in opposite directions by contacts operated by a rock-shaft on which 95 the needle or galvanometer-bar of the Wheatstone bridge is mounted, substantially as described. 100

4. The combination, with a galvanometer, of a separate motor and circuit, a shunt apparatus consisting of two pairs of disks upon each side of the axis of the galvanometer-needle, one disk in each pair being connected to an opposite brush of the motor and the other disk in each pair to an opposite pole of the 110 motor-battery, a pair of metal contacts tilted by the deflection of the galvanometer-needle to make contact with the disks on either side and close the motor-circuit in either direction, a drum revolved by the shaft of the motor and having a series of resistances which are inserted and cut out by the revolution of the 115 drum in opposite directions, a series of indicator-circuits all connected up in the galvanometer-circuit, a series of thermometers each 120 having a series of resistances which are cut out and inserted by the rise and fall of the mercurial column, an index revolved by the motor, and means for closing each indicator-circuit separately, substantially as described. 125

5. A thermometer having a mercury-vessel provided with a non-conducting indicating-tube for the mercurial column, said tube provided with a series of steel needles entering 130

the mercury-channel, said needles connected, successively, by resistance-coils, a conducting-wire in circuit with the mercury-reservoir, and a separate wire in circuit with the upper 5 one of the series of spiral resistances surrounding the thermometer-tube, substantially as described.

6. A thermometer having a mercurial reservoir, a screw cap or nut having adjustment in the mouth of said reservoir, a second nut having adjustment in a central opening in the first nut, an ebonite tube having a channel for the mercurial column, a series of steel needles entering said channel, a series of equal 15 resistances connecting the needles from the bottom to the next above throughout the series, a metal cap in connection with the upper resistance-coil and having an overflow-opening, a binding-post in electrical connection with the mercury-reservoir, and a separate binding-post in electrical connection with the metal cap of the thermometer-tube, substantially as described.

7. A thermometer having a metal reservoir 25 for the mercury, a metal cap or nut adjustable in the mouth of said reservoir, a second nut adjustable in an opening of the first, and an ebonite tube having a series of resistances cut out and inserted by the rise and fall of 30 the mercurial column, respectively, substantially as described.

8. The combination, with a galvanometer, of a drum having a series of resistance-coils, their terminals connected to a corresponding 35 series of insulated metal plates arranged on the face of said drum, a connection between

one terminal of the galvanometer-coil and the shaft of the drum, an arm on the shaft connecting with the last plate on the drum, said plate and the one adjacent having electric connection with opposite terminals of adjacent resistance-coils of the drum, a brass spring bearing on the plates of the drum as the latter revolves and connected with one pole of the battery, a connection between the other 40 pole of the battery and the other terminal of the galvanometer-coil, said connection broken beneath a series of circuit-closing keys, a series of indicator-circuits connected to said keys, a series of thermometers interposed in 45 said indicator-circuits, each thermometer having a series of resistances cut out and inserted by the rise and fall of the mercurial column, a connection between the several indicator-circuits and the first terminal of the galva- 50 nometer-coil, a motor having a separate circuit, a shunt closing the circuit of the motor in opposite directions, a motor-shaft rotating the drum carrying the resistances and also rotating a shaft moving an index over a suitable 55 dial, and a series of keys corresponding with the thermometers and adapted to close each thermometer-circuit separately, substantially as described.

In testimony whereof we have affixed our 60 signatures in presence of two witnesses.

FREDERICK W. WIESEBROCK.
ERNST HUBER.
